B. E. WASHBURN

WINDOW LOCK

Filed March 10, 1922.

FIG. 1.

FIG. 2.

FIG. 3.

FIG. 4.

INVENTOR

Bert E. Washburn.

U. S. Pat. Off.

Batty

UNITED STATES PATENT OFFICE.

BERT E. WASHBURN, OF PEORIA, ILLINOIS.

WINDOW LOCK.

Application filed March 10, 1922, Serial No. 542,550.

To all whom it may concern:

Be it known that I, BERT E. WASHBURN, a citizen of the United States, and a resident of Peoria, in the county of Peoria and State 5 of Illinois, have invented certain new and useful Improvements in Window Locks, of which the following is a full, clear, and exact description, reference being had to the accompanying drawing, forming part of this 10 specification.

My invention relates primarily to devices which are attached to the sash and casings of windows whereby the sash may be locked either opened or closed.

One object of my invention is the provision of a mechanism which is entirely concealed from view and which will effectually 15 lock the sash in any adjusted position.

Another object of my invention is to provide a structure which will prevent the sash from rattling in the frame.

Another object of my invention is the provision of means for adjusting the tension of the locking devices.

Other objects of my invention will appear and be described in the specification.

The novelty of my invention will be hereinafter more fully set forth and specifically pointed out in the claim.

In the accompanying drawing:

Fig. 1 is a broken view of a typical window frame and sash, viewed from the inside of a room and showing all of my device that appears on the finished structure.

Fig. 2 is an enlarged broken sectional view of a portion of Fig. 1, showing the general arrangement of the parts.

Fig. 3, is a side view of Fig. 2.

Fig. 4, is an enlarged detail of the part of 40 the mechanism shown in Fig. 2.

The same numerals of reference are used to indicate identical parts in all the figures.

Referring more particularly to Fig. 1, the ordinary window comprises a frame 1, stool 45 2, upper sash 3, and lower sash 4.

A key hole plate 5 is carried by the frame 1 adjacent the meeting rails of the sash, this plate preferably being provided with two key holes.

As shown more clearly in Fig. 2, the lower sash 4 is plowed as at 6 to receive a species 50 of rack bar 7, this bar being turned over as at 8 at the upper portion of the sash and similarly turned over at the lower portion 55 so that the rack bar 7 is firmly held in place against longitudinal movement. The upper

sash 3 is similarly plowed and a similar rack bar inserted.

The locking mechanism is carried on a plate 9 which is secured to the jamb, the latter being mortised to receive the locking mechanism which, as shown more clearly in Fig. 4, comprises a gear 10 suitably mounted on bearings in the side pieces 11 and 12 and 60 13 which are angularly arranged and adapted to engage the teeth of rack bar 7. The racks 12 and 13 pass through the plate 9 and are guided and held in mesh by the guides 14 and 15 which are carried by the side plates 11. Each of the racks 12 and 13 65 is provided with a lug 16 against which a compression spring 17, bears, the other end of the compression spring being engaged by a suitable washer 18 carried by the end of an adjusting screw 19 which passes through 70 a portion of the guide 14 and 15, and by means of which the tension of springs 17 75 may be regulated as desired.

A spring 20 is mounted adjacent to the gear 10, the latter carrying a projection 21 80 which is adapted to cooperate with the spring 20 to hold the parts in unlocked position.

Any suitable key may be employed to engage the allotted opening in gear 10 to rotate the latter in either direction to operate the device.

By arranging the racks 12 and 13 on an angle as shown, the device will lock the sash against movement in either direction and afford a plurality of contacts with the rack bar 7 thereby increasing the amount of 90 resistance offered to a movement of the window sash when the device is locked.

It is to be noted that the locking mechanism for each sash is arranged adjacent that face of the sash which is toward the inside of the room so that the locking mechanism is placed as far from exposure to the weather as possible, and also that the locking mechanism is placed so as not to interfere with the sash cord which is usually mounted at the center of the thickness of the sash.

As shown in Figs. 2 and 3, to prevent the sash weights from striking the locking mechanism a guard 22 is mounted in the weight box above the locking mechanism and if desired a similar guard may be placed below the locking mechanism so that the weights in ascending or descending will be guided in 100 110 passing the locking mechanism to prevent contact therewith.

It will be observed that from the construction shown either sash may be locked in any position in the frame.

It is to be noted that the springs 17 may be adjusted through the medium of the screws 19 to force the racks 12 and 13 against the racks bar 7 to prevent the window from rattling by forcing the sash against the jamb opposite from that which carries the locking mechanism.

Having thus fully described my invention, I claim—

In a window lock the combination of a rack bar movable relatively to locking mechanism, and a locking mechanism comprising a pair of locking members arranged at sub-

stantially equal angles on opposite sides of a line at right angles to the relative movement between the rack bar and the locking mechanism and in the place of this movement, and an adjustable spring tension device for causing the engagement of the locking members with the rack bar under sufficient tension to prevent the window from rattling, rack teeth carried from each locking member, which gear engaging the rack teeth from moving the locking members, a projection on the gear, and a spring operated device for engaging the projection to hold the parts in unlocked position.

BERT E. WASHBURN.
